MINING MACHINE

Original Filed June 18, 1923

UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

MINING MACHINE

Original application filed June 18, 1923, Serial No. 646,001. Divided and this application filed January 19, 1925. Serial No. 3,487.

My invention relates to mining machines and more particularly to mining machines of the flexibly fed type.

An object of my invention is to provide an improved mining machine. Another object of my invention is to provide an improved mining machine feeding means including feed operating and takeup mechanisms on the machine. A still further object of my invention is to provide an improved mining machine of the room and pillar type wherein improved means are provided for feeding and controlling the machine during cutting. A still further object of my invention is to provide an improved mining machine wherein the same may be fed in opposite directions during cutting without reversing the driving motor. Still another object of my invention is to provide an improved mining machine wherein improved transmission means are provided between the driving motor and the feed and takeup members whereby a more flexible operation of the machine is obtained. These and other objects and advantages of my invention will, however, hereinafter more fully appear.

In the accompanying drawings I have shown for purposes of illustration one form which my invention may assume in practice.

In these drawings,—

Fig. 1 is a plan view, partially in section, of a mining machine of the room and pillar type incorporating my improved mechanism.

Fig. 2 is a side elevation of the receding side of the machine shown in Fig. 1.

Fig. 3 is a partial side elevation of the advancing portion of the machine shown in Fig. 1.

In this illustrative form of my invention, which is a division of my copending application Ser. No. 646,001, filed June 18, 1923, I have shown a mining machine comprising a machine frame 1 adapted to slide on its bottom 2 on the mine bottom laterally relative to a flexible feeding means of any suitable form preferably adapted to provide advance and receding portions, herein in the form of a chain 3, and having a rigid cutter bar 4 projecting longitudinally therefrom at the front end thereof and a cutter bit carrying cutter

chain 5 is adapted to be circulated about the bar in a well known manner.

Referring more particularly to the machine it will be noted that an electric motor 6 is disposed transversely of the front end of the machine frame 1, the motor being disposed over the cutter bar 4 as is usual in room and pillar machines, while driving connections are provided between this motor and a feeding mechanism similar to that described in the above mentioned copending application, and other driving connections are provided between the motor and a usual cutter chain driving sprocket 7 located beneath the rear of the machine and driving the cutter chain 5 on the bar 4. Referring more specifically to these connections it will be noted that herein the motor armature shaft carries a single pinion 8 meshing with an intermediate spur gear 9 suitably journaled on a transverse axis in the machine frame and in turn meshing with a like spur gear 10 keyed to a transverse shaft 11 disposed between the motor and the feeding mechanism previously mentioned. As illustrated, this shaft 11 is suitably journaled at its opposite ends in the opposite sides of the frame and carries a plurality of bevel pinions 12 and 13 adapted to cooperate selectively with an upstanding bevel gear 14 operatively connected to the cutter chain driving sprocket 7, the direction of rotation of the latter depending upon the position of a clutch member 15 splined to the shaft and having clutch teeth at opposite ends adapted to alternatively engage the members 12 and 13. Thus it will be evident when the position of the member 15 is adjusted by a suitable clutch controlling mechanism 16 it is possible to drive or disconnect the cutter chain 5 whenever desired or to rotate the cutter chain in different directions without reversing the direction of the motor.

Operatively connected to the shaft 11 so as to be driven thereby when desired and whether the cutting mechanism is operating or thrown out of operation is the feeding mechanism previously mentioned. In this construction it will be noted that a pinion 17 is keyed to the shaft 11 and meshes directly with the fast feed gear 18 of the feeding

mechanism keyed, as at 19, to a suitable sleeve 20 disposed coaxially with a transverse shaft 21 disposed parallel with and in the rear of the shaft 11. The gear 18 is adapted to drive the shaft 21 through a suitable friction clutch mechanism, generally designated 22, at a fast or haulage speed. It will also be noted that the end of the shaft 11 opposite from the gear 10 has keyed thereto a pinion 23 which meshes with a spur gear 24 freely rotatable on the shaft 21 and which has secured thereto and rotatable therewith a pinion 25 which meshes with a spur gear 26 journaled on the shaft 11 between the bevel gear 13 and the pinion 23 and this gear has secured thereto and rotatable therewith a pinion 27 which meshes with a spur gear 28 keyed, as at 29, to a sleeve 30 rotatable upon the shaft 21. The gear 28 is adapted to drive the shaft 21 through a suitable friction clutch mechanism, generally designated 31, at a slow or cutting speed. The friction clutches 22 and 31 are herein under control of a shipper 32 operated by a lever 33 on the rear end of the machine frame. Further it will be noted that detachably secured to opposite ends of the transverse shaft 21 as by suitable jaw clutches 34 and 35 operated by levers 36 and 37 is a feed operating member 38 and a takeup member 39. From the foregoing description it will be clearly evident that the members 38 and 39 may be driven from the motor in one direction at fast or slow speeds simultaneously or independently and that a variation of these speeds may be obtained by the varying of the amount of application of the clutches 22 and 31. The members 38 and 39 herein also have drum members 40 and 41 respectively secured thereto provided with friction surfaces on their exterior periphery with which brake bands 42 and 43 cooperate, these bands being operated by suitable levers 44 and 45 carried by the rear end of the machine frame. Cooperating with the feed operating member 38 and the takeup member 39 is the flexible feeding member or chain 3. Herein with the machine operating from the right hand rib to the left hand rib to make a room and pillar cut it will be noted that the advancing portion of the chain 3 extends from a suitable anchor, not shown, at the left hand rib along the face beneath a transposable front guide 46, then rearwardly and upwardly around an idler sprocket 47 beneath the feed operating member 38 and then upwardly and transversely across the top of the machine in a guide channel 48 and then downwardly beneath the takeup member 39 and forwardly and upwardly over an idler sprocket 49 and hence rearwardly over a guide roll 50 and around guide rolls 51 and 52 rotatable on vertical axes at the rear end of the machine frame, the receding portion of the chain extending rearwardly to a suitable anchor, not shown, at the right hand rib in a well known

manner. It will also be evident that with such a construction it is made possible to operate the feeding and cutting mechanism in opposite directions without reversing the motor, the feeding mechanism being reversely operated by reversing the arrangement of the flexible feeding means while the cutting mechanism is reversely operated by changing the connection of the clutch shipper 15 and by reversing the cutter bits in their respective links, suitable guide rolls 53 and 54, similar to the guides 50 and 51, being utilized at this time to guide the feed chain. In order to enable this reverse operation the front guide 46 is transposed to the opposite side of the machine frame. It will herein further be noted that a sprocket 55 shown in dotted lines in Fig. 1 may also be detachably secured to the takeup member 39 to drive the transport truck in a well known manner and that a suitable starting and stopping controller is provided for the motor 6, as indicated at 56.

In the operation of my improved construction the machine when unloaded from its transport truck, not shown, is preferably brought up to a position adjacent the face at the right hand rib of the coal and the advancing portion of the chain 3 is then attached to a suitable jack at the left hand rib while the receding portion is attached to a suitable jack at the right hand rib in the usual manner. The motor is then started and the cutter chain clutch thrown in to actuate the cutter chain in the desired direction. The jaw clutch 34 is then thrown out and the jaw clutch 35 thrown in whereupon by applying the friction clutch 31 the bar is sumped or fed in under the coal, the takeup member 39 drawing in the chain at a slow or cutting speed while the feed operating member 38 slowly pays it out under control of the brake band 42. After the sumping cut is completed the jaw clutch 35 is thrown out and the clutch 34 is thrown in and by then applying the friction 31 the machine is caused to cut transversely across the face at a cutting speed. When the machine reaches the end of its transverse cut it is angled and backed out in a well known manner.

As a result of my invention it will herein be noted that as a result of a possibility of employing a motor constantly rotating in the same direction it is made possible to eliminate any necessity for the provision of a reversible motor or complicated reversing mechanism therefor, the motor being capable of being controlled through the simple stopping or starting controller 56. Attention is also directed to the fact that inasmuch as the motor may operate continuously at full speed when desired, i. e., not only during cutting but during unloading, loading, and transport, it is made possible not only to eliminate the difficulties arising from making and breaking of circuit connections and thereby

render the machine more safe in gaseous mines but also to simplify the controlling mechanism. These and other advantages of my invention will, however, be clearly apparent to those skilled in the art.

5 While I have in this application specifically described one form which my invention may assume in practice, it will be understood that this form of the same is shown for purposes of illustration and that the same may be modified and embodied in various other forms without departing from its spirit or the scope of the appended claims.

What I claim as new and desire to secure by Letters Patent is:

15 1. In a mining machine, a transversely disposed electric motor, reversible cutting mechanism, feeding mechanism including a feed operating member and a takeup member, each 20 of said members having the same mode of operation during either operation of said cutting mechanism, flexible feeding means cooperating with said members, and means to drive said cutting mechanism and the machine during cutting in either direction without reversing said motor.

25 2. In a mining machine, a driving motor disposed at the forward end of the machine, feeding mechanism driven thereby including a transversely disposed shaft, means to drive said shaft from said motor at a plurality of predetermined speeds, means to vary said speeds, a feed operating member and a takeup member, and means to releasably connect the 35 same to said shaft.

30 3. In a mining machine, a driving motor disposed at the forward end of the machine, feeding mechanism driven thereby including fast and slow speed gearing, a transverse shaft driven thereby, friction means to vary the speed of said shaft, a feed operating member and a takeup member, means to connect said members to said shaft, and friction means to control said members when released 45 therefrom.

35 4. In a mining machine including a machine frame, a driving motor carried by the forward end thereof, cutting mechanism driven thereby including a driving element for said cutting mechanism disposed at the rear of said motor and a rigid cutter bar extending forwardly lengthwise of the machine frame during cutting, and feeding means driven by said motor including a feed member 50 and a takeup member independently or simultaneously rotatable by power in the same direction at different speeds.

55 5. In a mining machine, a motor disposed at the forward end of the machine, cutting mechanism driven by said motor including a rigid cutter bar extending forwardly lengthwise of the machine during cutting, and feeding mechanism driven by said motor including a shaft disposed transversely of the machine, and fast and slow speed friction oper-

ating clutches arranged coaxially with said shaft.

6. In a mining machine, a motor disposed at the forward end of the machine, cutting mechanism driven by said motor including a rigid cutter bar extending forwardly lengthwise of the machine during cutting, and feeding mechanism driven by said motor including a transversely disposed horizontal shaft, a feed member and a takeup member disposed coaxially with said shaft, and fast and slow speed friction operating clutches for said members arranged coaxially with said shaft.

7. In a mining machine, a motor disposed at the forward end of the machine, cutting mechanism driven by said motor including a rigid cutter bar extending forwardly lengthwise of the machine during cutting, and feeding mechanism driven by said motor including a horizontal shaft, feed and takeup members arranged coaxially with said shaft, fast and slow speed friction clutches arranged coaxially with said shaft for controlling said members, and controlling clutches interposed between said members and said clutches.

8. In a mining machine, a driving motor disposed at the forward end of the machine, cutting mechanism driven by said motor including a rigid cutter bar extending forwardly lengthwise of the machine during cutting, feeding mechanism driven by said motor including a feed operating member, and mechanism for enabling the machine to cut in opposite directions in accordance with the room and pillar system of mining without reversing said motor or the direction of rotation of said feed operating member.

9. A mining machine having reversible cutting mechanism thereon including a rigid cutter bar extending forwardly lengthwise of the machine during cutting, feeding mechanism thereon including a feed operating member and a takeup member, said members having the same mode of operation in either direction of cutting of said mechanism, a driving motor disposed at the forward end of the machine, and mechanism for enabling the machine to cut in opposite directions in accordance with the room and pillar system of mining without reversing said motor or reversing the direction of rotation of said feed operating and take-up members.

10. A mining machine having cutting mechanism thereon including a rigid cutter bar extending forwardly longitudinally of the machine during cutting, feeding mechanism thereon including a feed operating member and a takeup member and flexible feeding means cooperating therewith, a driving motor disposed at the forward end of the machine, and mechanism for enabling said machine to cut in opposite directions in accordance with the room and pillar system of min-

ing without changing the arrangement of said flexible means on said members.

11. A mining machine having reversible cutting mechanism thereon including a rigid cutter bar extending forwardly longitudinally of the machine during cutting, feeding mechanism thereon including a feed operating member and a power driven takeup member and flexible feeding means cooperating therewith, said feed operating member and takeup member both being rotatable at similar cutting speeds to wind in said flexible means, a driving motor disposed at the forward end of the machine, and mechanism for enabling said machine to cut in opposite directions in accordance with the room and pillar system of mining without reversing said motor.

12. A mining machine having reversible cutting mechanism thereon including a rigid cutter bar extending forwardly longitudinally of the machine during cutting, feeding mechanism thereon including a feed operating member and a power driven takeup member, said feed operating and takeup members both being rotatable at a similar cutting speed, a driving motor disposed at the forward end of the machine, and mechanism for enabling said machine to cut in opposite directions in accordance with the room and pillar system of mining.

13. A mining machine normally slidable upon a mine bottom having cutting mechanism thereon including a rigid cutter bar extending forwardly longitudinally of the machine during cutting, feeding mechanism thereon including a feed operating member and a power driven takeup member and flexible feeding means cooperating therewith, both said feed operating member and takeup member being rotatable at a plurality of speeds including a cutting speed to wind in said flexible means, a driving motor disposed at the forward end of the machine, and mechanism enabling said machine to cut in opposite directions in accordance with the room and pillar system of mining without reversing said motor.

14. A mining machine normally slidable upon a mine bottom having cutting mechanism thereon including a rigid cutter bar extending forwardly longitudinally of the machine during cutting, feeding mechanism thereon including a feed operating member and a takeup member and flexible feeding means cooperating therewith, a motor disposed at the forward end of the machine for driving said mechanisms, and mechanism for enabling said machine to cut in opposite directions in accordance with the room and pillar system of mining without reversing said members or changing the arrangement of said flexible means on said members.

15. A mining machine normally slidable upon a mine bottom having cutting mecha-

nism thereon including a rigid cutter bar extending forwardly longitudinally of the machine during cutting, feeding mechanism thereon including a feed operating member and a controlling member and flexible feeding means cooperating therewith, a motor disposed at the forward end of the machine for driving said mechanisms, and mechanism for enabling said machine to cut in opposite directions in accordance with the room and pillar system of mining without reversing said motor or said members and without changing the arrangement of said flexible means on said members.

16. A mining machine normally slidable upon a mine bottom having cutting mechanism thereon including a rigid cutter bar extending forwardly longitudinally of the machine during cutting, feeding mechanism thereon including a feed operating member and a takeup member and flexible feeding means cooperating therewith, a motor disposed at the forward end of the machine for driving said mechanisms, and mechanism for enabling said machine to cut in opposite directions in accordance with the room and pillar system of mining without reversing said members or said motor or changing the arrangement of said flexible means on said members.

17. A mining machine normally slidable upon a mine bottom comprising cutting mechanism including a longitudinally projecting cutter bar extending forwardly of the machine during cutting, feeding mechanism including a feed operating member, a driving motor disposed at the forward end of the machine, mechanism for driving said cutting mechanism in opposite directions without reversing said motor, a flexible feeding member cooperating with said feed operating member, and means for feeding said machine in opposite directions in accordance with the room and pillar system of mining without reversing said feed operating member or changing the arrangement of said flexible member on said feed operating member.

18. In a mining machine, a driving motor disposed at the forward end of the machine, cutting mechanism driven thereby including a longitudinally projecting rigid cutter bar extending forwardly of the machine during cutting, a feed operating member and a takeup member, flexible feeding means cooperating therewith having free end portions adapted to be drawn in by different members relative thereto, and means driven by said motor adapted to actuate either member to wind in either portion at variable speeds or at the same speed without reversing said motor.

19. In a mining machine, a motor disposed at the forward end of the machine, cutting mechanism driven thereby including a driving element for said cutting mechanism disposed at the rear of said motor and a rigid

- cutter bar extending forwardly of the machine during cutting, a feed operating member, a takeup member, a continuous flexible feeding member cooperating therewith having free end portions adapted to be drawn in by different members relative thereto, and means driven by said motor adapted to actuate either member to wind in either portion at variable speeds or at the same predetermined speed. 10
20. In a mining machine, a motor disposed at the forward end of the machine, cutting mechanism driven thereby including a rigid cutter bar extending forwardly longitudinally of the machine during cutting, and feeding mechanism driven by said motor including a transverse shaft, a feed operating member, a takeup member, and means to connect said members directly to said shaft, and friction means for controlling said members when released from said shaft. 15
21. In a mining machine, a frame slidable on the mine bottom during cutting and supporting a motor, said motor being disposed at the forward end of the machine, cutting mechanism driven by said motor including a rigid cutter bar extending forwardly longitudinally of the machine during cutting, and driving means for said cutting mechanism including a transverse shaft, a feed operating member, means for connecting said member to said second mentioned shaft, and friction means for controlling said member when released from said second mentioned shaft. 25
22. In a mining machine, a motor disposed at the forward end of the machine, cutting mechanism driven by one end of said motor including a rigid cutter bar extending forwardly longitudinally of the machine during cutting and feeding mechanism driven by said end of said motor including a transverse shaft, a feed operating member, a takeup member, and releasable means for connecting said members directly to said shaft. 40
23. In a mining machine, a motor, and cutting and feeding mechanisms driven by said motor including parallel horizontal cutter and feed driving shafts disposed at the rear thereof and independently operable feed operating and take-up members driven through said shafts. 50
24. In a mining machine, a driving motor, and cutting mechanism driven by said motor including a cutter bar projecting in advance of said motor and a transverse shaft disposed in a horizontal plane in the rear of said motor and a reversing mechanism for said cutting mechanism arranged coaxially with said shaft. 55
25. In a mining machine, a frame slidable on the mine bottom during cutting and supporting a driving motor, reversible cutting mechanism driven by said motor including a shaft extending transversely of the machine and a clutch disposed coaxially therewith, and feeding means driven by said motor including feed gearing driven by said transverse shaft. 70
26. In a mining machine, a frame slidable on the mine bottom during cutting and supporting a driving motor, reversible cutting mechanism driven by said motor including a shaft extending transversely of the machine and a clutch disposed coaxially therewith, reverse gearing driven thereby, and means for selectively connecting said gearing to said shaft, and feeding mechanism driven by said motor including feed gearing driven by said transverse shaft. 75
27. In a mining machine, a frame slidable on the mine bottom during cutting, a motor on said frame, reversible cutting mechanism driven by said motor including a shaft disposed parallel with the axis of said motor, and feeding means driven by said motor including feed gearing arranged coaxially with said parallel shaft. 80
28. In a mining machine, a frame slidable on the mine bottom during cutting, a motor on said frame, reversible cutting mechanism driven by said motor including a shaft disposed parallel with the axis of said motor, and feeding means driven by said motor including fast and slow speed gearing including gears arranged coaxially with said parallel shaft. 85
29. In a mining machine, a driving motor disposed at the forward end of the machine, and reversible cutting mechanism driven thereby including a driving element therefor disposed at the rear of said motor and a forwardly projecting rigid cutter bar extending in advance of said motor, a shaft extending transversely of the machine, and a clutch disposed coaxially therewith, said clutch being shiftable in opposite directions relative to said shaft for effecting drive of said cutting mechanism in opposite directions. 90
30. In a mining machine, a driving motor disposed at the forward end of the machine, reversible cutting mechanism driven thereby and including a driving element therefor disposed at the rear of said motor and a forwardly projecting rigid cutter bar extending in advance of said motor, a shaft extending transversely of the machine, a clutch disposed coaxially therewith, reverse gearing driven thereby, and means for actuating said clutch in opposite directions for alternatively connecting said gearing to said shaft. 105
31. In a mining machine, a horizontal motor disposed transversely of the machine, reversible cutting mechanism driven thereby including a forwardly projecting rigid cutter bar and a shaft disposed parallel with the axis of said motor, and feeding means driven by said motor operatively connected 115
32. In a mining machine, a frame slidable on the mine bottom during cutting, a motor on said frame, reversible cutting mechanism driven thereby including a driving element therefor disposed at the rear of said motor and a forwardly projecting rigid cutter bar extending in advance of said motor, a shaft extending transversely of the machine, a clutch disposed coaxially therewith, reverse gearing driven thereby, and means for actuating said clutch in opposite directions for alternatively connecting said gearing to said shaft. 120
33. In a mining machine, a frame slidable on the mine bottom during cutting, a motor on said frame, reversible cutting mechanism driven thereby including a driving element therefor disposed at the rear of said motor and a forwardly projecting rigid cutter bar extending in advance of said motor, a shaft extending transversely of the machine, a clutch disposed coaxially therewith, reverse gearing driven thereby, and means for actuating said clutch in opposite directions for alternatively connecting said gearing to said shaft. 125
34. In a mining machine, a frame slidable on the mine bottom during cutting, a motor on said frame, reversible cutting mechanism driven thereby including a driving element therefor disposed at the rear of said motor and a forwardly projecting rigid cutter bar extending in advance of said motor, a shaft extending transversely of the machine, a clutch disposed coaxially therewith, reverse gearing driven thereby, and means for actuating said clutch in opposite directions for alternatively connecting said gearing to said shaft. 130

to said transverse shaft for drive by the latter.

32. In a mining machine, a machine frame 5 slidable on its bottom on the mine bottom, a motor having but a single rotor and having said rotor extending transversely of the machine, reversible cutting mechanism driven thereby including a forwardly projecting rigid cutter bar and a shaft disposed parallel 10 with the axis of said rotor, and feeding means driven by said motor operatively connected to said transverse shaft.

33. In a mining machine, a driving motor disposed at the forward end of the machine, 15 feeding mechanism driven thereby and disposed at the rear thereof including a transversely disposed shaft, means to drive said shaft from said motor at a plurality of predetermined speeds, means to vary said speeds, 20 a feed operating member and a take-up member, and means to releasably connect said members to said shaft.

34. A mining machine normally laterally 25 slidable upon a mine bottom during cutting comprising cutting mechanism including a forwardly projecting rigid cutter bar, feeding mechanism including a feed operating member, a driving motor disposed at the forward end of the machine, mechanism for 30 driving said cutting mechanism in opposite directions without reversing said motor, a flexible feeding member cooperating with said feed operating member, and means for feeding said machine in opposite directions 35 in accordance with the room and pillar system of mining without reversing said feed operating member or changing the arrangement of said flexible member on said feed operating member.

40 35. A mining machine normally laterally slidable upon a mine bottom during cutting comprising cutting mechanism including a forwardly projecting rigid cutter bar, feeding mechanism including a plurality of feed 45 operating members, a driving motor disposed at the forward end of the machine, mechanism for driving said cutting mechanism in opposite directions without reversing said motor, flexible feeding means having 50 feeding portions cooperating with said feed operating members, and means for feeding said machine in opposite directions in accordance with the room and pillar system of mining without reversing said feed operating members or changing the arrangement 55 of said flexible feeding means on said members.

36. In a mining machine, a driving motor disposed at the forward end of the machine, 60 cutting mechanism including a rigid forwardly projecting cutter bar, means for driving said cutting mechanism from said motor including a driving element therefor disposed at the rear end of the latter, feeding mechanism including a rotatable feed oper-

ating member and a rotatable take-up member and cooperating flexible feeding portions, one adapted to be wound in by each member, and positively operable means driven by said motor adapted to rotate said members simultaneously in a similar manner to wind in at a plurality of speeds. 70

37. In a mining machine, a driving motor, reversible cutting mechanism driven thereby including mechanism disposed at the rear of 75 said motor, and feeding mechanism disposed at the rear of said motor including a plurality of feed operating members each rotatable in a similar manner during cutting in opposite directions without reversing said motor. 80

38. In a mining machine, a driving motor disposed at the forward end of the machine, cutting mechanism driven by said motor including a rigid cutter bar extending forwardly longitudinally of the machine during cutting, means driven by said motor for feeding said machine laterally during cutting including fast and slow speed gearing, a transverse shaft driven thereby, friction 85 means to vary the speed of said shaft, a feed operating member and a take-up member, means to simultaneously connect said members to said shaft for rotation therewith, and friction means to control said members when 90 released from said shaft. 95

39. In a mining machine, a driving motor disposed at the forward end of the machine, cutting mechanism driven by said motor including a rigid cutter bar extending forwardly longitudinally of the machine during cutting, means driven by said motor for feeding said machine laterally during cutting including fast and slow speed gearing, a transverse shaft driven thereby, friction 100 means to vary the speed of said shaft, a feed operating member and a take-up member, means to either selectively or simultaneously connect said members to said shaft for rotation therewith, and friction means to control said members when released from said shaft. 105

40. A mining machine normally slidable upon a mine bottom having cutting mechanism thereon including a rigid cutter bar extending forwardly longitudinally of the machine during cutting, feeding mechanism thereon including a feed operating member and a take-up member disposed on axes extending transversely of the machine, a motor disposed at the forward end of the machine for driving said mechanisms, and mechanism for enabling said machine to cut in opposite directions in accordance with the room and pillar system of mining without reversing said members. 115

41. In a room and pillar mining machine, a frame slidable on its bottom on the mine bottom, a motor carried thereby at the forward end thereof, reversible cutting mechanism driven by said motor including a driv- 120

ing element therefor disposed at the rear of said motor and a rigid cutter bar extending forwardly lengthwise of said frame during cutting, feeding mechanism including a feed operating member and a take-up member, each of said members having the same mode of operation during either operation of said cutting mechanism, flexible feeding means cooperating with said members, and means 10 to drive said cutting mechanism and the feeding mechanism during cutting in either direction without reversing said motor.

42. In a room and pillar mining machine, a frame slideable on its bottom on the mine bottom, a motor carried thereby at the forward end thereof, cutting mechanism driven by said motor including a driving element therefor disposed at the rear of said motor and a rigid cutter bar extending forwardly 20 lengthwise of the machine during cutting, and feeding mechanism driven by said motor including a transversely disposed shaft, means to drive said shaft at a plurality of predetermined speeds, means to vary said 25 speeds, and a feed operating member and a take-up member, and means for releasably connecting said members to said shaft for rotation therewith.

43. In a room and pillar mining machine, 30 a frame slideable on its bottom on the mine bottom, a motor carried thereby at the forward end thereof, cutting mechanism driven by said motor including a driving element therefor disposed at the rear of said motor and a rigid cutter bar extending forwardly 35 lengthwise of the machine during cutting, and feeding mechanism driven by said motor including fast and slow speed gearing, a transverse shaft driven thereby, friction 40 means to vary the speed of said shaft at any speed, a feed operating member and a take-up member, means to connect said members and said shaft, and friction means to control said members when released from said shaft.

44. In a mining machine, a machine frame slideable on its bottom on the mine bottom, a motor on said frame, cutting mechanism driven by said motor including a transverse shaft arranged between the motor and one 50 end of said frame, and feeding mechanism driven by said motor including a feed operating member and a take-up member, said members being relatively rotatable and adapted to cooperate with flexible feeding 55 means, and operative driving connections between said transverse shaft and said members.

45. In a room and pillar mining machine, 60 a machine frame slideable on its bottom on the mine bottom, a motor on the forward end of said frame, cutting mechanism driven by said motor including a rigid cutter bar extending forwardly lengthwise of said frame during cutting, said cutting mechanism also including a transverse shaft located rear-

wardly of said motor, and feeding mechanism driven by said motor including a feed operating member and a take-up member, and operative driving connections between said transverse shaft and said members. 70

46. In a room and pillar mining machine, a machine frame slideable on its bottom on the mine bottom, a motor on the forward end of said frame, cutting mechanism driven by said motor including a rigid cutter bar extending forwardly lengthwise of said frame during cutting, said cutting mechanism also including a transverse shaft located rearwardly of said motor, and feeding mechanism driven by said motor including a feed 75 operating member and a take-up member, and operative driving connections between said transverse shaft and said members including a transverse shaft arranged in the rear of and parallel with said first mentioned shaft. 80

47. In a room and pillar mining machine, a machine frame slideable on its bottom on the mine bottom, a motor on the forward end of said frame, cutting mechanism driven by said motor including a rigid cutter bar extending forwardly lengthwise of said frame during cutting, said cutting mechanism also including a transverse shaft located rearwardly of said motor, and feeding mechanism 90 driven by said motor including a feed operating member and a take-up member, and operative driving connections between said transverse shaft and said members including a transverse shaft arranged in the rear of and parallel with said first mentioned shaft, and fast and slow speed clutches arranged coaxially with said last mentioned shaft. 95

48. In a room and pillar mining machine, a machine frame slideable on its bottom on the mine bottom, a motor on the forward end of said frame, cutting mechanism driven by said motor including a rigid cutter bar extending forwardly lengthwise of said frame during cutting, said cutting mechanism also including a transverse shaft located rearwardly of said motor, and feeding mechanism driven by said motor including a feed operating member and a take-up member, and operative driving connections between said transverse shaft and said members including a transverse shaft arranged in the rear of and parallel with said first mentioned shaft, said feed operating member and take-up member being arranged coaxially with said last mentioned shaft. 100

49. In a room and pillar mining machine, a machine frame slideable on its bottom on the mine bottom, a motor on the forward end of said frame, cutting mechanism including a rigid cutter bar extending forwardly longitudinally of said frame during cutting and driving means for said cutting mechanism including a transverse shaft located 110 120 130

rearwardly of said motor, and feeding means driven by said motor including a transverse shaft arranged parallel with and rearwardly of said shaft, fast and slow speed driving connections between said first shaft and said second shaft, and a plurality of relatively rotatable feed operating members driven by said second shaft.

50. In a room and pillar mining machine, a machine frame slidable on its bottom on the mine bottom, a motor on the forward end of said frame, cutting mechanism including a rigid cutter bar extending forwardly longitudinally of said frame during cutting, and driving means for said cutting mechanism including a transverse shaft located rearwardly of said motor, and feeding means driven by said motor including a transverse shaft arranged parallel with and rearwardly of said shaft, fast and slow speed driving connections between said first shaft and said second shaft, and a plurality of relatively rotatable feed operating members arranged coaxially with and driven by said second shaft.

51. In a room and pillar mining machine, a machine frame slidable on its bottom on the mine bottom, a motor on the forward end of said frame, cutting mechanism including a rigid cutter bar extending forwardly longitudinally of said frame during cutting, driving means for said cutting mechanism including a transverse shaft located rearwardly of said motor and a reversing mechanism for said cutting mechanism including gears arranged coaxially with said shaft, and feeding means driven by said motor including a transverse shaft arranged parallel with and rearwardly of said shaft, fast and slow speed driving connections between said first shaft and said second shaft, and a plurality of relatively rotatable feed operating members driven by said second shaft.

52. In a room and pillar mining machine, the combination with a main frame adapted to rest upon and slide in any direction over the mine bottom, of cutting mechanism including an elongated kerf cutter projecting forwardly lengthwise of said frame during cutting, and a driving element for said cutting mechanism disposed at the rear end of said frame, a plurality of rotatable feed operating members mounted upon said frame with their axes extending transversely thereof, power devices upon the frame, and control mechanism adapted to connect said feed operating members with said power devices to cause said members to revolve in winding direction either simultaneously or separately at relatively high speed or at relatively low speed, and a clutch mechanism for each feed operating member and adapted to connect said members separately or simultaneously with said power devices and to

permit rotation of said feed operating members independently of each other.

53. In a room and pillar mining machine, the combination with a main frame adapted to rest upon and slide in any direction over a mine bottom, of cutting mechanism including an elongated rigid kerf cutter projecting forwardly longitudinally of said frame during cutting, and a driving element for said cutting mechanism disposed at the rear end of said frame, a plurality of feed operating members mounted on said frame with their axes extending transversely thereof and adapted to cooperate with flexible feeding means, power devices on said frame, control mechanism adapted to connect said feed operating members with said power devices to cause said members to revolve in winding direction either simultaneously or separately at relatively high speed or at relatively low speed or to permit them to revolve in the unwinding direction under frictionally controlled resistance, and means to control the actuation of each of said members independently of each other.

54. In a room and pillar mining machine, the combination with a main frame adapted to rest upon and slide in any direction over a mine bottom, of cutting mechanism including an elongated rigid kerf cutter projecting forwardly longitudinally of said frame during cutting and a driving element for said cutting mechanism disposed at the rear end of said frame, a plurality of feed operating members mounted on said frame with their axes extending transversely thereof and adapted to cooperate with flexible feeding means, power devices on said frame, control mechanism adapted to connect said feed operating members with said power devices to cause said members to revolve in winding direction either simultaneously or separately at relatively high speed or at relatively low speed or to permit them to revolve in the unwinding direction under frictionally controlled resistance or to permit them to revolve in unwinding direction without such resistance, and means to control the actuation of each of said members independently of each other.

55. In a mining machine, a frame slidable on its bottom on the mine bottom, a motor carried by said frame and having a horizontal power shaft, reversible cutting mechanism driven by said motor including a forwardly projecting rigid cutter bar, and driving means for said cutting mechanism including a shaft disposed parallel with said motor power shaft, and feeding means driven by said motor operatively connected to said second mentioned shaft and including a feed operating member adapted to cooperate with flexible feeding means.

56. In a mining machine, a frame slidable on its bottom on the mine bottom, a motor

- carried by said frame at the forward end thereof and having a driving element, cutting mechanism driven by said motor including a driving element disposed at the rear 5 thereof, a cutter bar projecting forwardly in advance of said motor, and mechanism for effecting reversal of said cutting mechanism while said motor driving element rotates in only one direction, and feeding means driven by said motor including a power operated feed operating member and a relatively rotatable power operated control member each adapted to cooperate with flexible feeding means.
- 15 57. In a mining machine, a frame slidable on its bottom on the mine bottom during the cutting operation, a motor carried thereby, cutting mechanism carried by said frame and driven by said motor including a forwardly 20 projecting cutter bar and driving means for said cutting mechanism including a transverse shaft, and reversing mechanism between said shaft and cutting mechanism whereby the latter may be driven in opposite 25 directions without reversing said motor, and feeding means driven by said motor including a shaft parallel with said transverse shaft and driven by the latter, plural speed transmission mechanism operatively connecting 30 said shafts including fast and slow speed friction clutches coaxial with said parallel shaft, a feed operating member and a controlling member each adapted to cooperate with flexible feeding means, and means for 35 simultaneously or separately operatively connecting said members to said parallel shaft.
58. In a mining machine, a frame slidable on its bottom on the mine bottom during the cutting operation, a motor carried thereby, 40 cutting mechanism carried by said frame and driven by said motor including a forwardly projecting cutter bar and driving means for said cutting mechanism including a transverse shaft, and reversing mechanism between 45 said shaft and cutting mechanism whereby the latter may be driven in opposite directions without reversing said motor, and feeding means driven by said motor including a shaft parallel with said transverse shaft 50 and driven by the latter, plural speed transmission mechanism operatively connecting said shafts including fast and slow speed friction clutches coaxial with said parallel shaft, a feed operating member and a controlling member arranged on axes parallel 55 to a line parallel with said parallel shaft and each adapted to cooperate with flexible feeding means, and means for simultaneously or separately operatively connecting said members to said parallel shaft.
- 60 59. In a room and pillar mining machine, the combination with a main frame adapted to rest upon and slide in any direction over the mine bottom, of cutting mechanism including an elongated kerf cutter projecting 65 forwardly lengthwise of said frame during cutting and a driving element for said cutting mechanism disposed at the rear end of said frame, a plurality of rotatable feed operating members mounted upon said frame 70 and each adapted to cooperate directly with flexible feeding means, power devices on said frame, and control mechanism adapted to connect said feed operating members with said power devices to cause said members to 75 revolve in winding direction either simultaneously or separately at relatively high speed or at relatively low speed, and a clutch mechanism for each feed operating member and adapted to connect said members separately 80 or simultaneously with said power devices and to permit rotation of said feed operating members independently of each other.
60. In a room and pillar mining machine, the combination with a main frame adapted 85 to rest upon and slide in any direction over a mine bottom, of cutting mechanism including an elongated rigid kerf cutter projecting forwardly longitudinally of said frame during cutting and a driving element for said cutting mechanism disposed at the rear end of said frame, a plurality of feed operating members mounted on said frame and adapted to cooperate directly with flexible feeding means, power devices on said frame, control 90 mechanism adapted to connect said feed operating members with said power devices to cause said members to revolve in winding direction either simultaneously or separately at relatively high speed or at relatively low 95 speed or to permit them to revolve in the unwinding direction under frictionally controlled resistance, and means to control the actuation of each of said members independently of each other.
61. In a room and pillar mining machine, the combination with a main frame adapted to rest upon and slide in any direction over a mine bottom, of cutting mechanism including an elongated rigid kerf cutter projecting 100 forwardly longitudinally of said frame during cutting and a driving element for said cutting mechanism disposed at the rear end of said frame, a plurality of feed operating members mounted on said frame and adapted to cooperate directly with flexible feeding means, power devices on said frame, control 105 mechanism adapted to connect said feed operating members with said power devices to cause said members to revolve in winding direction either simultaneously or separately at relatively high speed or at relatively low speed or to permit them to revolve in the unwinding direction under frictionally controlled resistance, and means to control the actuation of each of said members independently of each other.
62. In a mining machine including a ma- 110

CERTIFICATE OF CORRECTION.

Patent No. 1,801,239.

Granted April 14, 1931, to

CHARLES F. OSGOOD.

It is hereby certified that error appears in the printed specification of the above numbered patent requiring correction as follows: Page 4, lines 25 to 27, claim 12, strike out "said feed operating and takeup members both being rotatable at a similar cutting speed," and insert instead and flexible feeding means cooperating therewith, said feed operating and takeup members both being rotatable at similar cutting speeds to wind in said flexible means,; and that the said Letters Patent should be read with this correction therein that the same may conform to the record of the case in the Patent Office.

Signed and sealed this 15th day of December, A. D. 1931.

M. J. Moore,
Acting Commissioner of Patents.
